US0D1013369S

(12) **United States Design Patent** (10) **Patent No.:** **US D1,013,369 S**
(45) **Date of Patent:** **** Feb. 6, 2024**

(54) **PHONE CASE**

(71) Applicant: **Jiqin Chen**, Shenzhen (CN)

(72) Inventor: **Jiqin Chen**, Shenzhen (CN)

(**) Term: **15 Years**

(21) Appl. No.: **29/894,335**

(22) Filed: **Jun. 8, 2023**

(30) **Foreign Application Priority Data**

Jun. 5, 2023 (CN) 202330339865.0

(51) **LOC (14) Cl.** **03-01**

(52) **U.S. Cl.**

USPC **D3/218; D3/249**

(58) **Field of Classification Search**

USPC D3/201, 218, 247, 249, 269; D13/107, D13/108, 118, 119; D14/217, 248, D14/250–253, 432, 440

CPC H04B 1/3888; H04M 1/0283; H04M 1/0202; A45F 2005/028; A45F 2200/0525

(57) **CLAIM**

The ornamental design for a phone case, as shown and described.

DESCRIPTION

FIG. 1 is a front view of a phone case showing my new design;

FIG. 2 is back view thereof;

FIG. 3 is a left view thereof;

FIG. 4 is a right view thereof;

FIG. 5 is a top plan view thereof;

FIG. 6 is a bottom plan view thereof;

FIG. 7 is a perspective view thereof;

FIG. 8 is a perspective view of the phone case in an alternate state of use; and,

FIG. 9 is another perspective view of the phone case in a second alternate state of use.

The broken lines illustrate portions of the phone case that form no part of the claimed design.

1 Claim, 9 Drawing Sheets
